UNITED STATES PATENT OFFICE.

LOUIS A. SAUER, OF WILLOWS, CALIFORNIA.

CHICK BROODER.

Application filed January 10, 1922, Serial No. 528,199. Renewed August 9, 1926.

This invention relates to improvements in brooders for chicks and similar small fowl or animals the principal objects of the invention being to provide a brooder in which 5 a large or small flock of chicks may be distributed into small groups; the chicks are prevented from crowding and piling on each other, thereby preventing smothering of the chicks; the chicks are always supplied with 10 fresh air; sanitary conditions are excellent; labor and care are reduced to a minimum, and the chicks may be seen at all times.

A further object is to provide means whereby the chicks will automatically learn 15 to roost.

Another object is to provide means for heating the brooder which while very efficient will be very economical of heat.

Still another object is to construct the 20 brooder in such a way that it may form a portable unit, which may be set in a horizontal position or at any desired incline.

Another object is to construct the brooder 25 so that it is adjustable and adaptable for different conditions, and may be used with or without heat, and with which, if intended to be heated, a minimum of damage will be wrought in the case of an accident to the heating means.

30 A further object of the invention is to produce a simple and inexpensive device and yet one which will be exceedingly effective for the purposes for which it is designed.

These objects I accomplish by means of 35 such structure and relative arrangement of parts as will fully appear by a perusal of the following specification and claims.

In the drawings similar characters of reference indicate corresponding parts in the 40 several views.

Fig. 1 is a side view of my improved brooder, half in section.

Fig. 2 is an end view of the same, showing 45 two compartments, one being in section, with the entrance runway removed.

Fig. 3 is a top plan view of a single brooder compartment, partly broken away.

Fig. 4 is a longitudinal section of a brooder 50 set in a building and on an incline, showing a roost in connection therewith.

Fig. 5 is a diagrammatic plan view of one form or design of a heat radiating system.

Fig. 6 is a similar view of another form.

Referring now more particularly to the 55 characters of reference on the drawings, the

numeral 1 denotes a plurality of spaced and parallel longitudinal and vertically disposed frames or walls, having screens 2 formed therewith and extending from top to bottom of the brooder space, and thereby dividing 60 the same into two longitudinal compartments.

Extending between and removably mounted on the frames or walls 1 are window members 3, beneath which, and spaced sufficiently therefrom to leave an air-space, are removable screen ceiling members, which 65 preferably rest on vertically adjustable cleats or supporting blocks 5.

Below the ceiling 4 a distance sufficient to 70 provide a brooding space therebetween are vertically adjustable and removable screened floor members 6 located between the top and bottom of the walls 1, the side-edge frames 7 of which floor are above the same, as shown 75 in Fig. 2, while the end frame members 8 are therebelow, as shown in Fig. 1, in order that there will be no obstructions for the passage of the chicks into the brooding space from the entrance-way 9 to the compartments at each end, and to permit of an even 80 alteration in depth of the brooding spaces.

The floors 6 may of course be placed level 85 with the ground or with the floor of a building, but for convenience with regard to further structural features, I prefer to raise the same somewhat, and to place inclined runways 10 leading to the entrances, which may if desired be normally closed by very flexible and easily moved flaps or curtains 11.

A suitable distance under the floors are 90 slidably mounted droppings pans 12, which makes the labor of keeping the brooder clean and sanitary, a very light task, these pans being also adjustable vertically, so as to conserve 95 heat and aid in ventilating.

To provide heat for the brooder, many and various ways are capable of being used. For instance as shown in Fig. 3, one or more transverse pipes or heat leads 13 may pass 100 under the floors 6 and above the pans at stated intervals, thus providing the greatest heat at certain specific points.

To gain a more even distribution of the heat, a number of heat radiators formed as 105 at 14 in Fig. 6 or as at 15 in Fig. 7 may be employed, as well as others of any shape or style desired, as for instance a stove or any other heat providing means.

The above forms however are included 110

and shown for purpose of illustration principally, as I wish it understood that I do not wish to confine myself to any particular kind of heat, whether steam, hot air, electrical, or otherwise; and any heat providing or radiating means used may be placed anywhere desired, or may be of a form taken from some other brooder designed such as to compel or instinctively cause the chicks 10 to separate or form into small groups.

Protecting plates or deflectors 13^a may be placed above the heat pipes or other members between the same and the floor on which the chicks stand both to protect the pipes 15 from the droppings and the chicks' feet, should it get too hot directly above said radiators.

By compelling the chicks to separate into small groups as above stated, it is possible 20 to safely have a large flock in a brooder without any partitions, and thus all separating walls when so desired may be dispensed with.

By installing the proper kind of heat 25 equipment to suit breeding conditions and with regard to the kind of heat used, the degree of heat may be regulated in each pen, as well as at any place in a pen or compartment; or the heat may be shut off entirely. For instance, when the atmosphere 30 is warm enough, heat may be dispensed within the entire brooder, and the windows and upper ceiling screen may both be removed.

Or if conditions and the location of the 35 brooder permit, some heat may be passed to the brooding spaces by reason of the windows, which concentrate any heat from the sun's rays, in the manner of a plant hot-house.

40 By reason of the screen-ceiling being adjustable, it may be positioned to just clear the backs of the chicks, so that they cannot pile up on top of each other, as they usually show an inclination to do; and which results in a certain number of them being 45 smothered to death, being unable to get fresh air. My brooder positively prevents this, not alone on account of the limited vertical height of the brooding space, but by reason of the floor being of screen which permits the passage of air therethrough and allows the chicks to breathe.

While I have specified "screen" for the various members, I do not wish to limit myself to the material usually designated as such, since any open-work material, suitable for the purpose and allowing the passage of air therethrough, may be used.

From their hatching, or when the chicks 60 are about three weeks old, the entire brooder; or that portion above the heating means, may be set at an angle, as shown at 16 in Fig. 4, the heating pipes 13 being arranged thereunder as before. The chicks using the brooder in this form, enter at the lower end,

and gradually walk up the floor 6^a, where they rest. At the upper end of the brooder, and leading therefrom, I provide a roost structure 17, the chicks gradually venturing out of the upper end of the brooder and onto said roost, thus automatically learning and acquiring the habit.

Placing the brooder on an incline will also tend to prevent the chicks from piling or pyramiding on each other, trampling and smothering some to death, since the pile will collapse and the chicks roll back free of each other as soon as the pile reaches a certain height or angle.

If the brooder should be set at such an 80 angle as to prevent the ready travel of the chicks up the same, cross cleats, as shown at 18 in Fig. 4, may be placed above the floor 6^a, to give the chicks additional hold, and to also teach them to roost.

It is to be understood that while I have shown the brooder mounted in a building with one end opening to the exterior thereof (see Fig. 4), the brooder may be placed in the center or any place on a floor. Also 90 suitable openings may be provided through the top of the brooder or elsewhere to allow for feeding of the chicks, which may also be used for entrance to and exit from the roosts.

The brooder can also be made or built directly into a suitable building, or made to be a corporate part of a small portable out-house if desired.

It is to be understood that while I have 100 shown and described certain specific forms and arrangements in construction, such forms and arrangements, both as to the size and number of pens or compartments, and the shape or style of walls, screens, platforms, aisles, heating means, etc., may be altered at will to suit different conditions, and the kind of fowl or animals to inhabit the brooder, so that latter, by making any necessary alterations, may be used for 110 other creatures besides chicks.

For instance, the previous floor and ceiling may be used to advantage for brooding purposes independent of the rest of the described structure, and collectively or singly, 115 and with or without heating means.

Either the flat or inclined form may thus be used.

Then again, the use of the previous ceiling in the brooder is not necessary under certain conditions, the brooding space being then adjusted for height by means of moving the roof or window up or down, which member may have double glass. Also the use of this ceiling depends on the growth and vitality of the chicks, and upon the means and manner of supplying the heat.

Also, while I have shown the principle of segregating the chicks by means of heat distribution, in a brooder, this principle may 130

be carried out for brooding purposes in any building and apart from a brooder, thus cutting down on the cost of construction.

It is also to be understood that the distance between the various heat leads or units will be varied according to the kind of heat used. The greater the concentration of heat, the closer may the leads be, thus causing the segregation of the chicks into very small batches. The heat leads may be parallel, or intersecting, and need not all be on the same horizontal plane, and they may be actually in the brooding space or above if desired.

While the droppings pans 12 are preferably used, the floor of the building may be used instead in order to cheapen the construction, though of course this arrangement is not so convenient.

I also wish it to be noted that I believe my method of heating a brooder has several advantages over any means now employed for this purpose. In the first place, piping, etc., is saved, next, the chicks are segregated in the proper manner, which is in small batches; third, most of the heat is supplied on the outside of each batch, which thus prevents the outside chicks of a batch from crowding and smothering the center ones, and they merely lean against each other as against a mother hen, which is natural; and finally the chicks, should they come in to the brooder from the cold, may get warmed quickly by reason of the greater heat provided at the certain points.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent, is:—

1. A brooder including a floor set at an angle, and forming the brooding place for the chicks, and a roosting means at the upper end of said floor and having communication therewith.

2. A brooder including enclosing walls, floor and ceiling members, said members being arranged to form a complete unit whereby the structure may be set at an angle, and roost means arranged at the upper end of the brooder, the latter being provided with an entrance passageway leading to the floor at its lower end and with a similar passageway at its upper end leading to the roost.

3. A brooder including floor and ceiling members, said members being arranged to form a complete unit whereby the structure may be set at an angle, and roost means arranged at the upper end of the brooder and communicating with the floor.

4. In a brooder, a floor pervious to air, and a heating means thereunder arranged to concentrate the heat at spaced points in the area of the floor, said floor and heating means being vertically adjustable relative to each other.

5. In a brooder, a foraminous floor, and a removable droppings pan under the floor and vertically adjustable relative thereto, whereby to enable ventilation and tempering condition in the brooder to be adjusted and controlled.

6. A brooder including a foraminous floor, arranged to support chicks, a droppings pan thereunder, and a heating means under the floor and above the pan and arranged both to supply heat to the chicks on the floor and to dry any droppings on the pan.

In testimony whereof I affix my signature.

LOUIS A. SAUER.
